UNITED STATES PATENT OFFICE.

JOHN W. PRICE, OF FLINT, ALABAMA.

WAGON-HUB.

1,264,434.

Specification of Letters Patent. Patented Apr. 30, 1918.

Application filed June 5, 1917. Serial No. 173,022.

To all whom it may concern:

Be it known that I, JOHN W. PRICE, a citizen of the United States, residing at Flint, in the county of Morgan and State of Alabama, have invented a new and useful Wagon-Hub, of which the following is a specification.

The present invention appertains to wheel hubs and mountings, and aims to provide a novel and improved hub construction and means for mounting the same.

The invention has for its object the provision of a hub mounted removably upon a spindle which is journaled underneath the axle tree, instead of having the hub journaled on an outstanding spindle, as usual, whereby the spindle rotates with the hub, to avoid the uneven wear of the spindle, as in ordinary running gears, wherein the lower portions of the spindles are worn away faster than the other portions thereof, resulting in the flattening thereof.

A further object of the invention is to provide a hub construction of the nature indicated which is simple, compact and inexpensive in construction, the hub and spindle being readily assembled and separated, and the hub being adjustable to tightly hold the spokes, whereby loose play can be taken up.

With the foregoing and other objects in view, which appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in the accompanying drawing, wherein:

Figure 1 is a median section of the device.

Fig. 2 is a cross section on the line 2—2 of Fig. 1, a portion of one of the hub plates being broken away, to show how the spokes fit together between the plates.

The numeral 1 designates the spindle, which is separate from the axle, and which rotates with the hub. This hub embodies a short bushing or sleeve 2 fitted upon the spindle 1 near its outer end, and adapted to be readily slipped onto and off of the spindle. The hub further includes a pair of circular side plates or disks 3 having central threaded openings 4 to threadedly engage the ends

of the bushing 2. The inner ends of the spokes 5 are fitted between the plates 3, and said plates are slightly conical, to hold the spokes 5 in dished form, as usual in wagon wheels. 60 The outer plate 3 can be tightened up, from time to time, to take up loose play of the spokes, and hold them rigidly in place. These plates 3 are preferably of sufficient diameter to brace the spokes, even without the 65 use of securing elements connecting said plates as ordinarily required in wheel hubs.

In order to lock the hub on the spindle, so that the spindle rotates therewith, a collar or plate 6 is secured upon the spindle 1, by 70 means of a set screw 6' or otherwise, and the inner plate 3 of the hub bears against this collar 6. The collar is provided at diametrically opposite sides of the spindle 1 with studs or pins 7 projecting outwardly, and 75 each of the plates is provided with a pair of diametrically opposite apertures or sockets 8, said apertures of the inner plate being adapted to receive the studs 7 when the hub 80 is slipped on to the spindle, whereby the hub is locked to the collar 6, to rotate therewith, while the collar is secured to the spindle, thus locking the hub and spindle together. The apertures 8 of the outer plate 3 can be used for the engagement of a suitable wrench 85 for tightening up the hub by rotating the outer plate 3. A nut 9 or other retaining element is engaged upon the outer terminal of the spindle 1 to hold the hub in place thereon against the collar 6. 90

The spindle 1 projects inwardly from the hub underneath one end of the axle tree A, and is journaled in a pair of bearings 10 mounted within the ends of a casing 11 secured to the axle tree underneath the same. 95 This casing 11 can act as a lubricant receptacle, for holding a lubricant to lubricate the contacting portions of the spindle and bearings. A nut 12 or other retaining element is engaged upon the inner end of the 100 spindle 1 and bears against the inner bearing 10 for holding the spindle assembled with the bearings, the collar 6 bearing against the outer bearing 10, and therefore serving as a spacer between the bearing and hub. By removing the nut 9, the wheel can be readily removed from the spindle, and by removing the nut 12, the spindle can be readily withdrawn from the bearings. The spindle and hub being detachable, enables 105 them to be shipped separately compactly, and with minimum expense. The spindle in

rotating with the hub will have the wear distributed evenly thereon, to avoid the flattening of the spindle, as is common with ordinary stationary spindles.

5 Having thus described the invention, what is claimed as new is:—

In a device of the character described, a spindle, a member secured thereon having studs, a hub embodying a bushing fitted removably on the spindle and plates threaded on the bushing, spokes fitted between said plates and clamped thereby, each plate having apertures, the apertures of one plate

being adapted to receive said studs, and the apertures of the other plate being for the engagement of a wrench, and means engaging the spindle for holding the hub thereon against said member.

In testimony that I claim the foregoing as my own, I have hereto affixed my signature 20 in the presence of two witnesses.

JOHN W. PRICE.
